UNITED STATES PATENT OFFICE

157,368

BOTTLE STOPPER

James Gould, Jr., Berlin, Conn., assignor to Tempo, Incorporated, New Haven, Conn.,
a corporation of Connecticut

Application July 12, 1947, Serial No. 140,253

Term of patent 7 years

(Cl. D58—10)

To all whom it may concern:

Be it known that I, James Gould, Jr., a citizen of the United States, residing at Berlin, in the county of Hartford and State of Connecticut, have invented a new, original, and ornamental Design for a Bottle Stopper, of which the following is a specification, reference being had to the accompanying drawing, forming part thereof.

Fig. 1 is a perspective view of a bottle stopper showing my new design; and

Fig. 2 is a top or plan view thereof.

I claim:

The ornamental design for a bottle stopper, substantially as shown.

JAMES GOULD, JR.
